LADY'S GARMENT

Dorine Gourdon, New York, N. Y., assignor to The Barbizon Corporation, New York, N. Y., a corporation of New York

Application May 8, 1946, Serial No. 668,243

4 Claims. (Cl. 2—73)

1

This invention relates to an improvement in women's garments, and more particularly to an improvement in slips or other undergarments, or nightgowns.

An object of the invention is to provide a garment made of a minimum number of separate pieces and in which the sewing operations to produce a garment of equal curve fitting qualities are reduced to a minimum.

Another object of the invention is to produce a garment having form-fitting qualities with freedom of movement for the wearer as a result of the angles of the seam lines.

Still another object of the invention is to provide a garment in which there are no vertical seams in the body section which would tend to flatten body curves and contours and restrain freedom of action.

Another object of the invention is to provide a garment wherein the seams are placed in the body section where restraint is necessary but do not appear where such restraint would impede freedom of movement.

A further object is to provide a garment wherein the location of the seams emphasize the desired curves or contours of the feminine body.

An additional object of the invention is to provide a garment construction in which the back yoke has a 45 degree bias which allows for greatest stretch where this stretch is essential for fit and comfort. This full stretch gradually diminishes as the yoke curves into the front midriff so that a substantially straight or non-stretching grain is provided where it is desirable to keep the garment in form and non-sagging.

Another object of the invention is to provide a garment having a substantially straight grain running from the point in the back where the shoulder strap is sewn to the outermost point of the midriff providing thus an anchor and thereby holding the garment in its proper place.

To the accomplishment of the foregoing and such other objects as may hereinafter appear, this invention consists in the novel construction and arrangement of parts hereinafter to be described and then sought to be defined in the appended claims, reference being had to the accompanying drawing forming a part hereof, which shows, merely for the purposes of illustrative disclosure, a preferred embodiment of the invention, it being expressly understood, however, that changes may be made in practice within the scope of the claims without digressing from the inventive idea.

2

In the drawing in which similar reference characters denote corresponding parts:

Fig. 1 is a front elevation of a slip embodying the invention;

Fig. 2 is a rear elevation of a slip embodying the invention; and

Fig. 3 is a plan view of the sheet of material from which the three parts forming the slip are cut, showing the patterns applied thereto for the front, back and bodice parts so that proper bias of the parts is provided.

Referring to the drawing, the slip comprises a front panel 10, cut from the sheet S so that its warp and woof threads are at substantially a 45 degree bias with the selvage of the sheet S. This front panel has a skirt portion *sk* flaring at its sides 12, 13 in usual manner toward the bottom edge 14. In its midriff portion M, the panel has oppositely located cut-outs 15, 16 having the curved edges 17, 18 that extend from the facing apices 19, 20. The opposite edges 21, 22 extend upwardly away from these apices toward the outer apices 23, 24, being interrupted by the triangular darts 25, 26. The edges 27, 28 slope upwardly in reverse direction from the apices 23, 24 to the upper apices 29, 30. The edges 31, 32 slope inwardly from the upper apices 29, 30 to the neck apex 33. The edges of the darts 25, 26 are sewed together so that the respective edges 21, 22 form continuous lines from the respective apices 19, 20 to apices 23, 24 to form in the upper or bust receiving portion of the panel P the breast cups U, V of the garment.

The rear panel 35 also is cut from sheet S on a 45° bias and has flaring side edges 36, 37 terminating in the bottom edge 38 and upper curved edges 39, 40 extending from the opposite side edges to an apex 41 that on the assembled garment lies opposite the midriff portion M of the front panel 10.

The bodice panel 43 also cut from sheet S on a 45° bias has a back portion 44 whose lower edges 45, 46 are complementary with the upper curved edges 39, 40 of the rear panel 35. The oppositely extending flaps 47, 48 have lower edges 45', 46' which are extensions respectively of curved edges 45, 46 and whose curvature is complementary to the curvature of edges 17, 18 of the front panel. The respective flaps 47, 48 have upper edges 49, 50 respectively extending from apices 53, 54 which are complementary in shape to the curved edges 21, 22 of the front panel 10 formed when the darts 25, 26 have been closed and the edges 51, 52 adjacent the apices 53, 54 extend in parallelism with respective edges 21, 22 adjacent respective apices

19, 20. The edges 51, 52 are joined respectively to edges 56, 55 and the latter edges 56, 55 extend respectively to apices 57, 58 and then as edges 59, 60, to an apex 61. The triangular flaps 62, 63 defined by the respective edges 55, 59 and 56, 60 lie substantially aligned with the corresponding triangular flaps formed by the respective edges 27, 31 and 28, 32 of the front panel 10.

Shoulder straps 64, 65 are attached to the pairs of apices 29, 57 and 30, 58.

In assembling the garment the rear panel 35 is sewed to the front panel 10 along the respective matching edges 12, 36 and 13, 37 forming side seams A and B in the skirt portion of the slip. The complementary edges 39, 46 and 40, 45 of the rear panel 35 and bodice panel 43 are sewed together to form the rear seams C, D.

The edges of the respective darts 25, 26 are sewed together to form seams E, F and the continuous curved edges 21, 22. Then the flaps 47, 48 are bent around and sewed along their curved edges 49, 50 to the curved edges 17, 18 of the front panel to form seams G, H and the curved edges 50, 49 are sewed to the edges 21, 22 to form the seams J, K. The edges 51, 52 are not visible on the external face of the garment as they provide for a seam allowance in making seams J, K. These edges 51, 52 extend parallel to edges 21, 22 inside the garment. The shoulder straps 64, 65 are then attached to the apices 29, 57 and 30, 58 of the front panel 10 and bodice panel 43 completing the garment.

Since all three panels are cut originally at a bias from the sheet S, they have the bias in the finished garment illustrated by the respective bias lines R, T, W shown in Figs. 1 and 2. As can be seen from Fig. 1, the bias of the front panel 10 denoted by the bias line R is substantially at right angles to the bias of the flaps 47, 48 denoted by bias line W. As can be seen from Fig. 2, the bias of the rear panel 35 denoted by bias line T is at right angles to that of the front panel 10. The bias lines of the front and rear panels from the side seams A, B extend at right angles to each other.

The seams J and K are located as to lie preferably below the wearer's breast lines and the bust portion B of the front panel which formed into cups U, V by the darts 25, 26 act as supports for the wearer's bust while the flaps 47, 48 fit snugly about the midriff portion of the wearer's body.

The three-piece garment formed by the three panels described accomplishes all the objects defined at the outset of this specification. Furthermore, fewer seams and consequently less sewing is required to assemble the garment from the panels.

Inasmuch as the seams in the construction described are stronger than the fabric, they are purposely so placed and are continuous as described so that the garment is not displaced nor has it any tendency to twist when the wearer moves. This is so because the lines of force and the stresses and strains to which the fabric may be subject are channelled into the seams and accordingly dissipate along their continuous and interposing lines; resulting thereby in effecting a resistance to displacement of the dissipation of these lines of force and stresses and strains in the seams, rather than through the body of the garment.

While a specific embodiment has been disclosed, variations within the scope of the claims is possible and is contemplated. There is no intention,

therefore, of limitation to the exact details shown and described.

What is claimed is:

1. A lady's garment of three bias cut fabric panels combined together to form the garment comprising a front panel of bias cut fabric having a skirt portion, a midriff portion and an upper bust portion, the midriff portion having cut-out portions with curved lower edges extending inwardly from opposite side edges, and the upper portion having darts whose edges are joined to define upper curved edges for said cut-out portions, a rear panel of bias cut fabric corresponding substantially in shape with the skirt portion of said front panel and joined along its side edges to corresponding side edges of the skirt portion, and having upper curved edges, and a unitary bodice panel of bias cut fabric having a rear portion whose lowermost edges are substantially complementary with and joined to the upper curved edges of said rear skirt panel, and said bodice panel having oppositely extending flaps substantially complementary in shape to the cut-out portions of said front panel, said flaps being bent to fit into said cut-out portions and being joined to the latter along the upper and lower curved edges thereof.

2. A lady's garment of three fabric panels combined together to form the garment comprising a front panel of fabric having a skirt portion, a midriff portion and an upper bust portion, the midriff portion having cut-out portions with curved lower edges extending inwardly from opposite side edges, and the upper portion having darts whose edges are joined to define upper curved edges for said cut-out portions, a rear panel of fabric corresponding substantially in shape with the skirt portion of said front panel and joined along its side edges to corresponding side edges of the skirt portion, and having upper curved edges, and a unitary bodice panel of fabric having a rear portion whose lowermost edges are substantially complementary with and joined to the upper curved edges of said rear skirt panel, and said bodice panel having oppositely extending flaps complementary in shape to the cut-out portions of said front panel, said flaps being bent around the sides and toward the front to fit into said cut-out portions and being joined to the latter along the upper and lower curved edges thereof.

3. A lady's garment of three fabric panels combined together to form the garment comprising a front panel of fabric having a flaring skirt portion, a midriff portion and an upper bust portion, the midriff portion having cut-out portions with curved lower edges extending inwardly from opposite edges thereof, the bust portion having triangular darts whose edges are joined to define bust-receiving cups whose lowermost edges are curved and constitute the curved upper edges of said cut-out portions, a rear panel of fabric corresponding substantially in shape with the flaring skirt portion of said front panel and sewed along its side edges to corresponding side edges of said front skirt portion, and having curved upper edges terminating in an apex laying opposite the midriff portion of said front panel, and a unitary bodice panel of fabric having a rear portion whose lowermost edges are substantially complementary with and sewed to the uppermost edges of said rear skirt panel, and having oppositely extending flaps whose curved edges are substantially complementary with and sewed to corresponding substantially complementary

curved edges of said front panel in its front portion, said flaps being adapted in the assembled garment to lie at the side and front of the body of the wearer and in the midriff section below the wearer's bust.

4. A lady's garment of three bias cut fabric panels combined together to form the garment comprising a front panel of fabric having a flaring skirt portion, a midriff portion and an upper bust portion, the midriff portion having 10 cut-out portions with curved lower edges extending inwardly from opposite edges thereof, the bust portion having triangular darts whose edges are joined to define bust-receiving cups whose lowermost edges are curved and constitute the curved upper edges of said cut-out portions, a rear panel of bias cut fabric corresponding substantially in shape with the flaring skirt portion of said front panel and sewed along its side edges to corresponding side edges of said front skirt portion, and having curved upper edges terminating in an apex lying opposite the midriff portion of said front panel, and a unitary bodice panel of bias cut fabric having a rear portion whose lowermost edges are complementary with and sewed to the uppermost edges of said rear

skirt panel, and having oppositely extending flaps whose curved edges are sewed to corresponding curved edges of said front panel in its front portion, said flaps being adapted in the assembled garment to lie at the side and front of the body of the wearer and in the midriff section below the wearer's bust and with the bias directions of the flaps as joined to said front panel substantially opposite to the bias direction of said front panel.
